INVENTOR

Nathan Ottinger

BY Carl P. Gepel

ATTORNEY

UNITED STATES PATENT OFFICE.

NATHAN OTTINGER, OF NEW YORK, N. Y.

CORRESPONDENCE DEVICE.

1,412,669.

Specification of Letters Patent. Patented Apr. 11, 1922.

Application filed April 27, 1917. Serial No. 164,968.

To all whom it may concern:

Be it known that I, NATHAN OTTINGER, a citizen of the United States of America, and a resident of the borough of Manhattan, in 5 the city, county, and State of New York, have invented certain new and useful Improvements in Correspondence Devices, of which the following is a specification.

The present invention relates to improvements in correspondence devices and more especially in devices intended for unsealed communications, advertisements or the like, although in several of the forms shown, the communication may also be sealed, if desired.

10 Among the purposes is to provide a cheap and inexpensive device which in the case of all the drawings shown herein can be cut or stamped from a single sheet of paper in one operation and in several of the forms it is 15 not even necessary to have any gumming or securing means whatsoever, other than the form of the device, and nevertheless, when the device is ready for mailing, a well secured packet is formed. In all of the devices shown in this invention, the device can 20 be inserted in a typewriting machine, press or other contrivance and the name and address be written at a single operation with the body of the correspondence.

25 30 With these and other objects in view, embodiments of my invention are shown in the accompanying drawings, and will be herein-after more fully described with reference thereto and finally pointed out in the claims.

35 In the accompanying drawings,

Figure 1 is a plan view of one form of my improved invention, showing the blank before folding.

Figure 2 shows the same in the form in 40 which it is preferably marketed.

Figure 3 shows the same addressed and ready for mailing.

Figure 4 is a plan view of a modified form of the invention.

45 Figure 5 shows the same ready for mailing.

Figure 6 is a perspective view of another modified form of my invention.

Figure 7 shows the same folded and ready 50 for mailing.

Figure 8 is a plan view of a further modified form of my invention.

Figure 9 shows the same folded and ready for mailing.

Figure 10 is a plan view of a still further 55 modified form of my invention.

Figure 11 shows the same folded and ready for mailing.

Figure 12 is a plan view of still another 60 form of my invention.

Figure 13 shows the same folded and ready to be written upon.

Figure 14 shows the same sealed and ready for mailing; and

Figure 15 is a rear plan view of another 65 form of my invention folded up and ready for mailing.

Similar reference characters indicate corresponding parts throughout the several figures of the drawings.

70 Referring to the drawings and more particularly to Figure 1 thereof, a portion A on a sheet of material is provided with a large opening between its two edges 35 which are adjacent a line of folding 31, such portion A is also provided with a central portion 20 which is provided with two extensions 20^a and 21 adapted to fold under said central portion. An edge 28 of the opening is bent along the line 27 in such manner that when 80 the portion A is folded down upon the portion B, the said bend will be towards the said portion B. This bend may be made by creasing or by applying some chemical or other material to accomplish the result. The 85 portion A is further provided with cuts 26 for the purpose of co-operating with the portions 22^a of the spring flaps 22 hereinafter described. The portion B is provided with flaps 22 along each of its edges 23, said flaps 90 being adapted to be bent over along the said edges and secured along the lines 24 to form spring flaps which can easily be moved backward or forward by means of cuts 24^a in the ends of the line of folding 31 and other 95 cuts 24^b in the ends of the line of folding 32. Said flaps are provided respectively with cut out portions 22^b to facilitate portions 22^a of said flaps being inserted between the portion 20 and the extensions 20^a and 21 by 100 means of which insertion interlocking means are formed. The portions C¹, D¹, C² and D² are additional writing portions attached to the portions C and D, and the line of folding 30 along which the portions C² and D² are 105 to be folded upon the portions C and D is slightly to the left of the perforated line 25 which is upon the portions A and B. Said

line of perforations 25 is at the left of the flap 22 when formed into a spring flap. The portion C is further provided with a cut 34 so placed as to engage over and hold closed 5 the corresponding part of the portion A when the latter is folded down.

Figure 2 shows the device complete and partially folded. In preparing the device for mailing, the portions C¹, D¹, C² and D² 10 are folded longitudinally along the lines of folding 29 and 30 and then the device is folded horizontally along the lines of folding 33, 32 and 31, and the portion A is then folded down, and the extensions 20^a and 21 15 are folded underneath the portion 20 and above the portion B so as to embrace the other folded portions of the device. The spring flaps 22 are then easily bent backward by means of the cuts 24^a and 24^b and their 20 free edges 22^a engage upon and embrace and close the open ends of the entire folded device. The portions 22^a of the said spring flaps are then inserted through the cuts 26 25 between the portion 20 and the extensions 20^a and 21 thus forming interlocking means. In folding the device as hereinbefore described the cut 34 in the portion C will engage over and close a corresponding part of portion A.

Figure 3 shows the device folded as aforesaid and ready for mailing.

If it be desired to have a sealed communication the entire spring flaps 22, though preferably not above the points 22^b, may be gummed and sealed to the device after it is 35 folded. If it be desired to open the device, if mailed in an unsealed condition, it is merely necessary to press back the spring flaps and then the contents are easily opened. If the device be sealed, it can easily be opened 40 along the perforated line 25 without tearing any of the contents which may then be easily unfolded.

It is obvious that the opening in the portion A can be given a rectangular, circular, 45 semi-circular, diagonal, irregular or any other shape, some of which are shown in the other drawings.

Figures 4 and 5 show a modified form of 50 my invention, intended to be used chiefly for unsealed communications. In this form, no gumming or securing means whatever, aside from the mere shape of the device, are used and yet a well secured and locked packet is produced. It is of the simplest and cheapest possible manufacture, being made from a single sheet, by a single stamping. Obviously, the flaps may, if desired, be made from separate pieces of material. The portion B is provided at its top with a portion 55 20 having extensions 20^a and 21, the flaps 22 are ordinary flaps without gumming and are provided with extensions 22^a. When the device has been written upon the portion C is folded upon the portion B along the line 60 of folding 32, the portion 20 is then bent over 65 the portion C, the extensions 20^a and 21 are folded under the portion C, and the part of the portion C which is embraced within the cut 34 is placed over the edge 28 of the portion 20. The flaps 22 are then placed over 70 the portion C and the parts 22^a of said flaps are placed under the portion 20, thus locking the device closed.

Figure 5 shows the device closed and ready for mailing. It is obvious that in 75 this form and indeed in all the forms shown in the drawings, additional writing space of practically any amount may be obtained by providing additional folds or sections below, or at the sides of, the portion C or 80 by additional sheets which may have prepared folds. The portion 20 may be of any depth not exceeding that of the portion B in this or any applicable modified form of the device.

Figure 6 shows another modified form of 85 my invention, chiefly for unsealed communications, forming a well secured packet without any gumming or sealing means upon the blank, which may be made by one cutting from a single sheet. The portion 20 is provided with extensions 20^a and 21, the lines of folding 29 and 30 being in line with the inner lines of the extensions 20^a and 21. The portions B¹ and C¹ are folded 90 along the line 29 and the portions B² and C² are folded along the line 30 and the device is then folded horizontally along the line of folding 32 upon the portion B. The portion 20 is then bent down over the portion C and the extensions 20^a and 21 are 95 then folded under the side openings formed between the portions B² and C², and B¹ and C¹.

Figure 7 shows the device ready for mailing. 100

Figure 8 shows another modified form of 105 my invention intended chiefly for unsealed communications. In this form, the opening in portion A is rectangular and the entire opening has a bent portion 28, similar to that described in Figure 1. The flaps 22 are spring flaps, extending along the entire edges 23 and adapted to be folded backward or forward by means of the cuts 24^a. 110

Figure 9 shows the same folded and ready 115 for mailing. The operation of this form is extremely simple. It is merely folded up along the lines of folding 33, 32 and 31 which may be prepared lines of folding, the portion A is then folded down and the spring flaps snapped so that their free edges 22^a engage upon and enfold the under side of the portion B. It is obvious that the spring flaps may be closed at either or both 120 ends to form pockets.

Figure 10 shows another modified form 125 of my invention, intended chiefly for unsealed communications, in which the portion B has a portion 20 without extensions, 130

attached along its upper edge and spring flaps along edges 23. The method of operation is similar to the form shown in Figures 8 and 9, except that the portion 20 is 5 folded down over the portion C when the device is folded, and the free edges 22^c of the flaps 22 engage upon and enfold the upper side of portion C.

Figure 11 shows this device ready for 10 mailing.

Figure 12 shows another modified form of my invention, intended for sealed communications. In this form there are no spring flaps or cuts. The flaps 22 are entirely 15 gummed, one of said flaps being on the portion A and the other on the portion B, and a perforated line 25 runs along the device and is located to the left of one of the flaps when in sealed position.

20 Figure 13 shows the same form ready to be written upon and Figure 14 shows it ready for mailing with the sealing flaps sealed, one upon the underside of the portion B and the other upon the upper side 25 of the portion C.

Figure 15 is a rear view of another modified form of my invention, folded up and ready for mailing and differs from the form shown in Figures 12, 13 and 14 in that the 30 flaps 36 and 37 are upon one fold, are un-gummed and are of such dimensions as to overlap each other and are provided with oppositely extending slits 36^a and 37^a respectively which permit the said extensions 35 to interlock with each other across the back of the device, thereby retaining the same securely folded, also no perforations are necessary in this form of my invention.

I have illustrated and described preferred 40 and satisfactory forms of my invention, but it is obvious that changes may be made therein within the spirit and scope thereof, as defined in the appended claims.

I claim:

45 1. In a device of the character described, a sheet of material foldable to form two or more folds, spring flaps on one of said folds in proximity to, and extending in the direction of, each of the edges of said fold which 50 are adjacent a line of folding, said fold forming one of the two exterior folds when said sheet is folded up, said flaps adapted to fold upon the outer surface of the other exterior fold and the fold which contains said flaps 55 being provided with cuts near the ends of said flaps, which are adapted to be partially secured to the fold containing them and partially free to form a spring retaining portion, said cuts being in a direction 60 transverse to the length of said flaps and adapted to form a flexible area adjacent said flaps to enable them to be bent backward or forward for the purpose of engaging more easily upon the outer surface of the other exterior fold.

2. In a device of the character described, a sheet of material foldable to form two or more folds, flaps on one of said folds in proximity to, and extending in the direction of, each of the edges of said fold which are adjacent a line of folding, said fold forming one of the two exterior folds when said sheet is folded up, said flaps adapted to fold upon the outer surface of the other exterior fold, each of said flaps being secured to said fold 70 containing member along a line intermediate its longitudinal edges and having one of its said edges free, the edges of said other folds being within the line of securing of said flaps and adapted to be received beneath said 75 flaps.

3. In a device of the character described, a sheet of material foldable to form three or more folds, certain of said folds constituting correspondence receiving folds, flaps on one 80 of said folds in proximity to, and extending in the direction of, each of the edges of said fold which are adjacent a line of folding, said fold forming one of the two exterior folds when said sheet is folded up, said flaps 85 adapted to fold upon the outer surface of the other exterior fold and means to seal said flaps upon such outer surfaces, but not upon said correspondence receiving folds, said exterior fold and said flaps adapted after sealing to constitute a permanent pocket from 90 which said correspondence receiving folds may be unfolded upon the unsealing of only one of said sealing flaps.

4. In a device of the character described, a 100 sheet of material foldable to form two or more folds, certain of said folds constituting correspondence receiving folds, flaps on one of said folds in proximity to, and extending in the direction of, each of the edges of said 105 fold which are adjacent a line of folding, said fold forming one of the two exterior folds when said sheet is folded up, said flaps adapted to fold upon the outer surface of the other exterior fold and means to seal said 110 flaps upon such outer surface, but not upon said correspondence receiving folds, and a line of perforations upon at least two folds and running transversely to said line of folding and so placed as to be interiorly removed 115 from said flaps when they are sealed, adapted to facilitate the opening of the said device.

5. In a device of the character described, a sheet of material foldable to form three or more folds, one end fold of said sheet being 120 wider than the other folds and adapted to have such excess width placed between the other folds when the sheet is folded up, and flaps on another fold having tabs adapted to be inserted between the first mentioned fold 125 and the excess width of said first mentioned fold when such excess width is folded under said first mentioned fold.

6. In a device of the character described, a sheet of material foldable to form three or 130

more folds, one end fold of said sheet being wider than the other folds and adapted to have such excess width placed between the other folds when the sheet is folded up, and 5 permanently folded spring flaps on another fold, said flaps having tabs adapted to be inserted beneath the first mentioned fold and the excess width of said first mentioned fold when such excess width is folded under said 10 first mentioned fold, said spring flaps adapted

to enclose and secure the side edges of said other folds when folded.

In testimony, that I claim the foregoing as my invention, I have signed my name in presence of two subscribing witnesses.

NATHAN OTTINGER.
